UNITED STATES PATENT OFFICE.

WALTER D. DAVIES, OF NEW YORK, N. Y., ASSIGNOR TO THE ANSONIA CLOCK COMPANY, OF SAME PLACE.

REPEATING ALARM-CLOCK.

SPECIFICATION forming part of Letters Patent No. 611,566, dated September 27, 1898.

Application filed June 30, 1898. Serial No. 684,788. (No model.)

To all whom it may concern:

Be it known that I, WALTER D. DAVIES, a citizen of the United States, and a resident of the borough of Brooklyn, in the city of New York and State of New York, have invented 5 a new and useful Improvement in Repeating Alarm-Clocks, of which the following is a specification.

This invention relates to what are known 10 as "repeating alarm-clocks"—that is to say, alarm-clocks in which the alarm mechanism when tripped or sprung operates during a series of recurring interrupted periods.

The object of this invention is to provide 15 in such an alarm mechanism an interrupting device which frees itself easily at the proper times for repetition and which while in operation produces only a very slight obstruction to the movement of the time-train of the clock; 20 and with this end in view the improvement consists in the interrupting mechanism hereinafter described and claimed.

Figure 1 is a vertical sectional view of such 25 of the parts of an alarm-clock movement as are necessary to illustrate the invention, the section being taken just inside of the back plate of the movement-frame. Figs. 2, 3, and 4 are views, taken in the opposite direction to Fig. 1, of the principal parts of the alarm-interrupting device, showing them in three different positions. Fig. 5 is a perspective view 30 of one part of said device.

Similar letters of reference designate corresponding parts in all the figures.

35 A designates the front plate of the frame of the clock-movement; C, the mainspring of the time-train; D, the winding-arbor of said spring, carrying the main wheel E, which gears with the center pinion a on the minute-hand arbor b; c, the arbor known as the "third-wheel" arbor, carrying the seconds-time pinion d and the third wheel e, said pinion d gearing with and receiving motion from the center wheel x.

40 F is the spring, and G the winding-arbor, of the alarm-train, the said arbor carrying the driving-wheel G', which operates through pinions f g and a wheel h to drive the arbor i of the escape-wheel i', which actuates the 45 alarm-hammer H through the verge j, to the arbor k of which the said hammer is attached.

The said arbor k is also provided with an arm l, which engages with the turned-in end of the trip-lever K, by which the alarm mechanism is locked until liberated by the tripping-cam B, which is shown in dotted outline in Fig. 1.

All the parts thus far described are the same as may be found in many alarm-clocks and have only been described here to illustrate 60 the application of my interrupting mechanism, which I will now proceed to describe in detail.

On one face of the wheel e there is a series 65 of contrate teeth s, which constitute practically a separate toothed wheel, and projecting from the verge-arbor k there is a rigid arm or tailpiece m, the lower end of which is turned toward the arbor c and has pivoted to it at n a tripping-piece I, of which Fig. 5 is a 70 perspective view and which is shown in all the other figures. This tripping-piece consists of a very small and light lever, having on one side a laterally-projecting tooth o and a laterally-projecting stop p and having applied between it and the tailpiece m or verge-arbor k a very light spring q, which tends to draw and hold the stop p against the end of the tailpiece m in such manner that the tooth o may either abut against one of the teeth s, 80 as shown in Fig. 2, and so stop the vibration of the alarm-verge, or may play back and forth through a space between two of said teeth, as may be understood by reference to Fig. 4, to permit the vibration of the verge. 85 The said spring is represented as a coil surrounding the arm or tailpiece m and having one end attached to the verge-arbor k and the other end connected with the stop p of the tripping-piece.

In Figs. 2, 3, and 4 the wheel e is, except 90 its contrate teeth s, only indicated by dotted circles, and the said teeth are shown in section, the body or disk of said wheel occupying a position in front of the tripping-piece, 95 so that if shown in full it would hide the tooth o.

The operation of this interrupting mechanism is as follows: When the alarm-verge is 100 liberated by the tripping of the locking-lever K, it is only free to vibrate and produce the alarm when the tooth o of the tripping-piece

I is opposite a space between two of the teeth *s* of the wheel *e*, its action being interrupted every time one of the teeth *s* arrives opposite the said tooth *o* and until in the rotation of 5 said wheel the tooth *s* passes said tooth *o* and leaves the latter free to pass to and fro between said tooth *s* and the next following tooth of the said wheel, thus permitting the operation of the alarm until it is interrupted 10 by the next tooth *s* presenting itself opposite the tooth *o*. In this operation the tripping-piece *I*, having a pivotal attachment to the arm *m*, plays an important part, as is illustrated by Figs. 2, 3, and 4. In Fig. 2 the tooth 15 *o* is represented as having been just arrested by one of the teeth *s*. In Fig. 3 the wheel *e* has advanced farther, and the friction produced between the two teeth *s o*, instead of producing such drag upon the time-movement 20 as would result if the tripping-piece or tooth *o* were rigidly attached to the arm *m*, simply causes the tripping-piece to turn on its pivot *n* and so to carry its tooth *o* in a direction outward from the axis of the wheel *e* until it 25 escapes from *s*. The spring *q* then by its instantaneous action on the tripping-piece throws the tooth *o* downward to a position opposite the space between the last-mentioned tooth *s* and the next one, as shown in Fig. 4, 30 and the alarm mechanism is then again freed, the tripping-piece *I* being then held securely in proper relation to the arm or tailpiece *m*

by means of the spring *q*, which holds the stop *p* against the bottom of the said arm or tailpiece.

35

What I claim as my invention is—

1. In an alarm-clock, the combination with a time-train and an alarm-train, of a striking-escapement in said alarm-train, a toothed interrupting-wheel in the time-train, a projection from the verge of said escapement, and a tripping-piece pivoted to said projection for alternately engaging with the teeth of said interrupting-wheel and vibrating uninterruptedly between the teeth of said wheel, substantially as herein described. 40

2. In an alarm-clock, the combination with a time-train and an alarm-train, of a striking-escapement in the alarm-train, a toothed interrupting-wheel in the time-train, a rigid projection from the verge of said escapement, a tripping-piece pivoted to the said projection for engagement with said interrupting-wheel and a spring applied between said tripping-piece and said projection, substantially as 50 and for the purpose herein described.

In testimony that I claim the foregoing as my invention I have signed my name, in presence of two witnesses, this 28th day of June, 1898.

WALTER D. DAVIES.
